AUXILIARY BERTH SECTION
ARRANGEMENT

James K. Tully, Alexandria, Va., and Basil E. Jones, Flossmoor, Ill., assignors to The Pullman Company, Chicago, Ill., a corporation of Illinois

Application May 1, 1942, Serial No. 441,416

14 Claims. (CL. 105—319)

This invention relates to railway sleeping cars and has for its principal object the provision of auxiliary sleeping space for the car porter without in any way encroaching upon the normally salable space within the car.

An important object of the invention is the provision of space for use by the porter convertible for day or night use and located adjacent the facilities in the car with which the porter's duties are associated.

Another object of the invention is the provision of a sleeping berth in the porter's section of an inconspicuous nature and which, when the space is made up for daytime occupancy, is not noticeable as such.

A further object of the invention is the provision of a porter's section having day and night facilities and in which the seat for day use is also available for use at night if desired even though the berth for night use is made up overhead.

The foregoing and other objects are attained by the arrangement illustrated in the accompanying drawings in which—

Fig. 1 is a general perspective view of the porter's section ready for daytime use showing the seat and having the berth disposed out of the way in its closed position;

Fig. 2 is also a general perspective view of the section, but made up ready for night use with the seat still available and showing the berth ready for occupancy with the curtains in place;

Fig. 3 is a general side elevational view of the porter's section and showing associated lockers and facilities with which the porter's duties are concerned and with the berth still made up for night occupancy;

Fig. 4 is a longitudinal sectional view through the porter's section taken on the line 4—4 of Fig. 7 showing the relative disposition of the various facilities associated therewith and depicting in broken lines the operation of the hinged folding panel for supporting the porter's bed;

Fig. 5 is a transverse sectional view taken on the line 5—5 of Fig. 7 through the section looking in one direction and showing the closed berth and seat in elevation;

Fig. 6 is a transverse sectional view taken on the line 6—6 of Fig. 7 through the section looking in the opposite direction and showing the lockers disposed in that wall and the support for the free end of the bed supporting panel;

Fig. 7 is a plan view of that portion of the car including the porter's section; and

Fig. 8 is a detail perspective view of the folding

strut for supporting the intermediate portion of the berth at the aisle when made up for night time use.

In Pullman sleeping cars it has been customary to provide the services of a porter for each car or a porter on call between two adjoining cars to look after the wants of the passengers and to perform various duties essential to the efficient operation of the cars and to the convenience of the passengers. It is, of course, necessary for the porter to have facilities for sleeping at night when his duties have all been performed and in open section cars it has always been possible to provide sleeping space in the relatively large men's general wash room which is incorporated in all cars of this type, but in cars, the plan of which provides only room accommodations with which this invention is primarily concerned and wherein general washrooms are not included, since these facilities are provided in each room, it becomes difficult at times to provide such sleeping facilities for the porter. Heretofore it has been the practice of the porter to make use of an unsold bedroom for this purpose but when all of the sleeping accommodations in a car or cars to which the porter is assigned have been sold it has been necessary for the porter to seek facilities elsewhere which is not always feasible because of the necessity of the porter's answering calls occurring in the cars in which he is on duty and then as frequently happens it is possible that all of the sleeping accommodations in an entire train may be sold. Under these circumstances the only alternative is to withhold sufficient sleeping accommodations from sale to care for all of the porters in a train and then objections are sometimes raised by passengers to the porters being assigned the same type of accommodations as they purchased. The invention proposes to overcome all of these difficulties by the provision of an auxiliary sleeping berth arrangement affording a permanent porter's section combined with the various locker space and facilities with which the duties of the porter are concerned and which includes a sleeping berth adapted to be folded out of the way in the daytime and which does not take up any of the space in the car normally sold to the traveling public.

In the drawings, 10 represents a railway car having a floor 11, a side wall 12 including a window 13 and a body end wall 14 including an end door 15. An aisle space 16 extends from the end door 15 to a passageway door 17 leading into the passageway through the passenger space (not shown). The passageway door 17 is hingedly

mounted in transverse bulkhead 18 which separates the passenger space from the end space defined by the body end wall 14 and the bulkhead. The passenger space accommodations comprise a plurality of private rooms (not shown) adapted each to provide facilities for one or more passengers depending upon the type of room such for instance, as bedrooms, compartments, drawing rooms or roomettes. The end space between the end wall 14 and bulkhead 18 as best shown in Fig. 7, is provided at one side of the aisle 16 with lockers 19 and 20 accessible from the aisle by means of doors 21 and 22 respectively and a general toilet 23 entrance to which is had from the aisle by means of door 24. At the opposite side of the aisle 16 from the general toilet and lockers 19 and 20 the porter's section 25 is disposed in this same end space between the wall 14 and bulkhead 18.

Ordinarily, in Pullman cars the space now occupied by this porter's section has been taken up by lockers and the like, but such lockers have been rearranged to provide all of the facilities heretofore to be had and at the same time made to afford room for the inclusion of a sleeping berth adapted to be folded out of the way when not in use. In the corner of the end space of the car formed by the side wall 12 and the end wall 14, an electric locker 26 is disposed which is formed by an aisle wall 27 and a transverse wall 28 extending from the side wall 12 to the aisle and forming the end partition of the porter's section 25 as more fully hereinafter will appear. A control panel 29 is located in the aisle wall of the electric locker, access to which is had from the aisle through a hinged door 30. The door to the control panel is kept locked at all times and may be opened only by use of the porter's key. The interior of the locker 26 is designed to accommodate various items of electrical equipment, only a few of which, 31 and 32, are illustrated, as best shown in Fig. 4 and is accessible from the porter's section space by means of pairs of upper and lower hinged doors 33 and 34, respectively, which also are kept locked at all times and may be opened only by the porter with his key. As best shown in Fig. 6 certain control switches 35 are disposed in a group on the exterior of the locker wall 28 in the porter's space for operation by him. An indicating light 36 is also disposed on the exterior of this wall for the attention of the porter. A horizontal ledge 37 is disposed on the wall 28 between the pairs of upper and lower doors 33 and 34 extending the width of the porter's berth hereinafter to be described and in position to be engaged on its upper surface by the free edge of the berth when the berth is in its extended position.

Opposite the electric locker and facing the wall 28 is the porter's seat 38 disposed between the side wall 12 and a seat end 39 at the aisle. It will be noted that the seat end 39 is of substantial depth to accommodate utility storage lockers disposed on the aisle side of the seat end in its lower portion and access may be had thereto by means of hinged mounted doors 40. Above the storage lockers in the upper portion of the thickened seat end a cabinet 41 is provided to enclose a water filter 42 and a goose-neck faucet 43 having valve 44 used in filling carafes 45 with filtered water for each of the individual rooms of the car. The filling mechanism is concealed by means of hinged door 46 which provides access to the cabinet from the aisle. The water piping for the filter and filling faucet is connected with

a cooling coil (not shown) located in an ice chest 47 which is disposed in the porter's section immediately in back of the seat and extending between the side wall 12 and the cabinet 41. The ice chest is heavily insulated as best shown in Fig. 4 and is filled through an insulated door 48 located in the top of the chest and hingedly mounted. The carafes 45 when not in use in the various passenger rooms are stored in special trays 49 designed for the purpose and located in storage locker 50 adjoining the ice chest and cabinet 41 whereby they may readily and conveniently be filled by the porter for distribution to the rooms. The storage locker 50 is closed by a hinged door 51 opening into the aisle alongside of cabinet door 46. Immediately above the locker door 51 an open faced receptacle 52 is provided which is adapted to contain telegraph message blanks and the like for the convenience of passengers.

It will be noted that all of the facilities thus far described are associated directly with the porter's space and located conveniently to his use with certain of them in the aisle also available to the passengers and including emergency tools (not shown) which are located in a container 53 disposed on the aisle wall opposite the porter's section (see Fig. 7). In the porter's section the seat 38 is available at all times but in order to permit a fully reclining position for sleeping, a folding berth is provided which may be extended for use above the seat but leaving the seat available for use. The berth and bedding therefor are accommodated in the space above the storage locker 50 and between the side wall 12 and the aisle. The berth storage space is disposed immediately above the plane of both the storage locker 50 and the top surface of the ice chest 47. The berth is comprised of a fixed section 54 overlying the locker 50 and folding panels 55 and 56 which are hinged together approximately midway of their total length as at 57 by means of continuous hinges and adapted to be extended from the closed position indicated in Fig. 1 to the operative position for use indicated in Fig. 2. The berth panel 56 is hingedly mounted with respect to the fixed portion 54 as at 58 and at its opposite margin is adapted to engage abutment 59 in the folded closed position as best shown in Fig. 4. The folding sections of the berth are shown in full lines in this figure in their folded fully closed position and shown in broken lines in two positions to indicate the operation thereof to fully extended mattress supporting position. It will be seen that the panel 55 is hingedly mounted to the panel 56 at that edge of the latter which swings on an arc about the hinge point 58 so that the hinge connection 57 between the two panels is disposed at the abutment 59 when the berth is closed up and the free edge of panel 55 is directed downwardly and adjacent to the fixed hinge edge 58 of panel 56. The surface of panel 55 is arranged flush with the surface 60 in the closed position of the berth and similar devices 61 are disposed at opposite sides of the panel 55 for locking both berth panels in fully closed position. The devices 61 comprise a catch 62 and a pivoted locking member 63 adapted to engage the catch. At that side of the berth adjacent the side wall 12 the catch 62 is located in the side of the recess receiving the berth and the locking member 63 is located upon the face of the panel 55 as best shown in Figures 2 and 5 but at the opposite side of the berth a wedge plate 64 taking the place of the catch 62 on this

side is disposed upon the surface of the panel 55 while the pivoted lock member 63 is secured upon the surface 60 in a position operatively to engage the wedge plate and hold the folded berth panels in closed position.

Upon release of the locking members 63 the folded berth is adapted to be extended from the closed position indicated in Fig. 4 to the fully open position shown in Fig. 3 at which time the free edge of the berth is supported upon the ledge 37 located on the surface of the electric locker 26 between the upper and lower doors 33 and 34. The free edge of panel 55 is thus supported by means of this ledge and the panel 56 is supported at its hinged edge 58 and by the ice chest 47 but additional support for both panels is provided adjacent the intermediate hinge 57. A pivotally mounted supporting strut 65 is disposed at the outside edge of the berth panels adjacent the aisle and as best shown in the fragmentary detail view illustrated in Fig. 8 is pivotally secured at 66 to the inside surface of the seat end 39. A limiting stop 67 confines the pivotal movement of the strut to the one hundred eighty degrees (180°) necessary to the swinging of the strut from the upright supporting position indicated in this figure to the depending inoperative position shown in Fig. 4. The berth supporting strut is provided with a flange portion 68 at its extremity which in the upright position of the strut is adapted to be entered into a recess 69 provided therefor in the under surface of panel 56 thereby securely to be maintained in supporting relation to the berth by reason of such interlocking association insured by the weight of the berth upon the strut. It will be noted that while the strut is engaged with the berth structure beneath panel 56 its engagement therewith is disposed immediately adjacent to the hinge 57 whereby to provide support for both of the berth panels through the medium of the hinge. At the side wall position the berth is similarly supported intermediate its ends by means of a ledge 70 secured to the side wall 12 in position to be engaged by the panel 56 when the berth is extended for use wherefore it will be seen that the berth when in its open position is supported for more than half its length at both sides and the greatest span between supports comprises the panel 55 from the hinge 57 to the ledge 37. Thus it will be seen that the extended berth panels provide a rigid supporting surface for the cushioned mattress 71 which is adapted to be stretched thereon to afford a comfortable sleeping accommodation for the porter. The mattress, as best shown in Fig. 4 together with a pillow and bedding 72 and 73 is stored in the compartment above the storage locker 50 formed by the closure of the berth panels 55 and 56 when the berth is not in use. A handhold 74 on the free extremity of the panel 55 provides for ready operation of the berth from closed to open position and vice versa.

When the berth is made up, access is had thereto from the aisle by means of a step 76 secured on the seat end 39 and a tread 11 also provided on the seat end at the armrest position. A grab-handle 78 secured to the ceiling affords means for the porter with which to pull himself upwardly and assist in entering the berth. A pair of curtains 75 which are stored with the bedding when not in use, are stretched across the berth for privacy and are suspended from a cord 79 which is stretched between the surface 60 and the face of the electric locker 26 adjacent the ceiling. The cord is maintained taut by means of a ten-

sion spring 80 and is secured to brackets 81 on the respective surfaces between which the cord extends.

A porter's call signal is provided closely adjacent to the sleeping berth in the form of a chime 82 located on the aisle side of the porter's section as shown in Figures 1, 2 and 3 of the drawings. Also as best shown in these figures it will be seen that the emergency cord fixture 83 is located conveniently to the porter regardless of whether the section is made up for day or night use.

From the foregoing it will be seen that an auxiliary berth section arrangement has been provided for railway sleeping cars having individual room accommodations exclusively wherein complete facilities for the porter are provided and which are located convenient to all appurtenances requiring the porter's attention and which are realized without encroaching upon otherwise normally usable space in the car but is had by combining existing facilities with the present arrangement in such manner as to afford improved accommodations for the porter and better planning of the existent facilities and of a generally acceptable nature.

What is claimed is:

1. In a railway sleeping car having a side wall and an aisle, an auxiliary sleeping berth section disposed between the side wall and the aisle and comprising a section space, a transversely disposed fixed seat in said space, a seat end construction at the aisle, utility lockers in the seat end accessible from the aisle, locker space adjoining the back of said seat between the side wall and seat end of greater height than the seat and accessible from the section space, a storage locker adjoining said locker space and accessible from the aisle, a compartment above said storage locker, a locker spaced from said seat defining the opposite end wall of said section space, upper and lower portions of said last-named locker accessible respectively from the section space and a portion accessible from the aisle, a foldable berth for the section space having a fixed portion overlying said storage locker and forming the bottom of said compartment, a pair of berth panels comprising a first panel hingedly connected at one end with said fixed portion and a second panel hingedly connected at one end to the opposite end of the first panel whereby to provide a full length berth foldable intermediate its ends and adapted to be extended from a folded vertical closed position to a horizontal open position on a plane with said fixed portion above said seat, the folded berth in its closed position being adapted to provide a closure for said compartment, locking means for holding the berth panels closed, said first panel in the extended position of the berth being adapted to be supported intermediate its ends upon said locker space whereby to provide headroom above said seat, means on the opposite end wall of the section space between said upper and lower portions for supporting the free end of said second panel, means for supporting the intermediate folding connection between said panels comprising a ledge on the side wall extending beneath the berth adjacent said connection and a strut member pivotally mounted on the seat end adapted to swing from an upright berth supporting position to a depending inoperative position, a mattress and bedding for the berth adapted to be stored in said compartment when the berth is closed, a removable curtain arrangement for the berth

including a supporting member having tensioning means incorporated therewith and adapted to be stretched between said compartment and the opposite end wall, and step means on the seat end construction affording access to the berth.

2. In a railway sleeping car having a side wall and an aisle, an auxiliary sleeping berth section disposed between the side wall and the aisle and comprising a section space, a transversely disposed fixed seat in said space, a seat end construction at the aisle, locker space adjoining the back of said seat between the side wall and seat end of greater height than the seat, a storage locker adjoining said locker space, a compartment above said storage locker, a locker spaced from said seat defining the opposite end wall of said section space, a foldable berth for the section space having a fixed portion overlying said storage locker and forming the bottom of said compartment, a pair of berth panels comprising a first panel hingedly connected at one end with said fixed portion and a second panel hingedly connected at one end to the opposite end of the first panel whereby to provide a full length berth foldable intermediate its ends and adapted to be extended from a folded vertical closed position to a horizontal open position on a plane with said fixed portion above said seat, the folded berth in its closed position being adapted to provide a closure for said compartment, locking means for holding the berth panels closed, said first panel in the extended position of the berth being adapted to be supported intermediate its ends upon said locker space whereby to provide headroom above said seat, means on the opposite end wall of the section space for supporting the free end of said second panel, means for supporting the intermediate folding connection between said panels comprising a ledge on the side wall extending beneath the berth adjacent said connection and a strut member pivotally mounted on the seat end adapted to swing from an upright berth supporting position to a depending inoperative position, a mattress and bedding for the berth adapted to be stored in said compartment when the berth is closed, a removable curtain arrangement for the berth including a supporting member having tensioning means incorporated therewith and adapted to be stretched between said compartment and the opposite end wall, and step means on the seat end construction affording access to the berth.

3. In a railway sleeping car having a side wall and an aisle, an auxiliary sleeping berth section disposed between the side wall and the aisle and comprising a section space, a transversely disposed fixed seat in said space, a seat end construction at the aisle, a storage locker of greater height than the seat and located in back thereof, a compartment above said storage locker, an end wall defining the opposite end of said section space, a foldable berth for the section space having a fixed portion overlying said storage locker and forming the bottom of said compartment, a pair of berth panels comprising a first panel hingedly connected at one end with said fixed portion and a second panel hingedly connected at one end to the opposite end of the first panel whereby to provide a full length berth foldable intermediate its ends and adapted to be extended from a folded vertical closed position to a horizontal open position on a plane with said fixed portion above said seat and providing headroom therefor, the folded berth in its closed position being adapted to provide a closure for said compartment,

partment, locking means for holding the berth panels closed, means on the opposite end wall of the section space for supporting the free end of said second panel, means for supporting the intermediate folding connection between said panels comprising a ledge on the side wall extending beneath the berth adjacent said connection and a strut member pivotally mounted on the seat end adapted to swing from an upright berth supporting position to a depending inoperative position, a mattress and bedding for the berth adapted to be stored in said compartment when the berth is closed, a removable curtain arrangement for the berth including a supporting member having tensioning means incorporated therewith and adapted to be stretched between said compartment and the opposite end wall, and step means on the seat end construction affording access to the berth.

4. In a railway sleeping car having a side wall and an aisle, an auxiliary sleeping berth section disposed between the side wall and the aisle and comprising a section space, a transversely disposed fixed seat in said space, a seat end construction at the aisle, a storage locker of greater height than the seat and located in back thereof, a compartment above said storage locker, an end wall defining the opposite end of said section space, a foldable berth for the section space having a fixed portion overlying said storage locker and forming the bottom of said compartment, a pair of berth panels comprising a first panel hingedly connected at one end with said fixed portion and a second panel hingedly connected at one end to the opposite end of the first panel whereby to provide a full length berth foldable intermediate its ends and adapted to be extended from a folded vertical closed position to a horizontal open position on a plane with said fixed portion above said seat, the folded berth in its closed position being adapted to provide a closure for said compartment, means on the opposite end wall of the section space for supporting the free end of said second panel, means for supporting the intermediate folding connection between said panels comprising a strut member pivotally mounted on the seat end adapted to swing from an upright berth supporting position to a depending inoperative position, a mattress and bedding for the berth adapted to be stored in said compartment when the berth is closed, a removable curtain arrangement for the berth including a supporting member having tensioning means incorporated therewith and adapted to be stretched between said compartment and the opposite end wall, and step means on the seat end construction affording access to the berth.

5. In a railway sleeping car having a side wall and an aisle, an auxiliary sleeping berth section disposed between the side wall and the aisle and comprising a section space, a transversely disposed fixed seat in said space, a seat end construction at the aisle, a compartment located in back of and above said seat, an end wall defining the opposite end of said section space, a foldable berth for the section space having a fixed portion forming the bottom of said compartment, a pair of berth panels comprising a first panel hingedly connected at one end with said fixed portion and a second panel hingedly connected at one end to the opposite end of the first panel whereby to provide a full length berth foldable intermediate its ends and adapted to be extended from a folded vertical closed position to a hor-

zontal open position on a plane with said fixed portion above said seat and providing headroom therefor, the folded berth in its closed position being adapted to provide a closure for said compartment, means on the opposite end wall of the section space for supporting the free end of said second panel, means for supporting the intermediate folding connection between said panels comprising a strut member pivotally mounted on the seat end adapted to swing from an upright berth supporting position to a depending inoperative position, a mattress and bedding for the berth adapted to be stored in said compartment when the berth is closed, a removable curtain arrangement for the berth adapted to be stretched between said compartment and the opposite end wall, and step means on the seat end construction affording access to the berth.

6. In a railway sleeping car having a side wall and an aisle, an auxiliary sleeping berth section disposed between the side wall and the aisle and comprising a section space, a transversely disposed fixed seat in said space, a compartment located in back of and above said seat, an end wall defining the opposite end of said section space, a foldable berth for the section space having a fixed portion forming the bottom of said compartment, a pair of berth panels comprising a first panel hingedly connected at one end with said fixed portion and a second panel hingedly connected at one end to the opposite end of the first panel whereby to provide a full length berth foldable intermediate its ends and adapted to be extended from a folded vertical closed position to a horizontal open position on a plane with said fixed portion above said seat and providing headroom therefor, the folded berth in its closed position being adapted to provide a closure for said compartment, means on the opposite end wall of the section space for supporting the free end of said second panel, means for supporting the intermediate folding connection between said panels comprising a strut member pivotally mounted on the seat end adapted to swing from an upright berth supporting position to a depending inoperative position, a mattress and bedding for the berth adapted to be stored in said compartment when the berth is closed and a removable curtain arrangement for the berth adapted to be stretched between said compartment and the opposite end wall.

7. In a railway sleeping car having a side wall and an aisle, an auxiliary sleeping berth section disposed between the side wall and the aisle and comprising a section space, a transversely disposed fixed seat in said space, a compartment located in back of and above said seat, an end wall defining the opposite end of said section space, a foldable berth for the section space having a fixed portion forming the bottom of said compartment, a pair of berth panels comprising a first panel hingedly connected at one end with said fixed portion and a second panel hingedly connected at one end to the opposite end of the first panel whereby to provide a full length berth foldable intermediate its ends and adapted to be extended from a folded vertical closed position to a horizontal open position on a plane with said fixed portion above said seat and providing headroom therefor, the folded berth in its closed position being adapted to provide a closure for said compartment, means on the opposite end wall of the section space for supporting the free end of said second panel, means for supporting the intermediate folding connection between said pan-

els comprising a strut member pivotally mounted on the seat end adapted to swing from an upright berth supporting position to a depending inoperative position, and a mattress and bedding for the berth adapted to be stored in said compartment when the berth is closed.

8. In a railway sleeping car having a side wall and an aisle, an auxiliary sleeping berth section disposed between the side wall and the aisle and comprising a section space, a transversely disposed fixed seat in said space, a compartment located in back of and above said seat, an end wall defining the opposite end of said section space, a foldable berth for the section space having a fixed portion forming the bottom of said compartment, a pair of berth panels comprising a first panel hingedly connected at one end with said fixed portion and a second panel hingedly connected at one end to the opposite end of the first panel whereby to provide a full length berth foldable intermediate its ends and adapted to be extended from a folded vertical closed position to a horizontal open position on a plane with said fixed portion above said seat and providing headroom therefor, the folded berth in its closed position being adapted to provide a closure for said compartment, means on the opposite end wall of the section space for supporting the free end of said second panel, and a mattress and bedding for the berth adapted to be stored in said compartment when the berth is closed.

9. In a railway sleeping car having a side wall and an aisle, an auxiliary sleeping berth section disposed between the side wall and the aisle and comprising a section space, a transversely disposed fixed seat in said space, a compartment located in back of and above said seat, an end wall defining the opposite end of said section space, a foldable berth for the section space having a fixed portion forming the bottom of said compartment, a pair of berth panels comprising a first panel hingedly connected at one end with said fixed portion and a second panel hingedly connected at one end to the opposite end of the first panel whereby to provide a full length berth foldable intermediate its ends and adapted to be extended from a folded vertical closed position to a horizontal open position on a plane with said fixed portion above said seat and providing headroom therefor, the folded berth in its closed position being adapted to provide a closure for said compartment, means on the opposite end wall of the section space for supporting the free end of said second panel, and a mattress and bedding for the berth adapted to be stored in said compartment when the berth is closed.

10. In a railway sleeping car having a side wall and an aisle, an auxiliary sleeping berth section disposed between the side wall and the aisle and comprising a section space, a transversely disposed fixed seat in said space, a foldable berth for the section space comprising a fixed portion above and to the rear of said seat and a pair of berth panels including a first panel hingedly connected at one end to said fixed portion and a second panel hingedly connected at one end to the opposite end of the first panel whereby to provide a full length berth foldable intermediate its ends and adapted to be extended from a folded vertical closed position to a horizontal open position on a plane above said seat and providing in open position sufficient headroom to permit the seat to be occupied and means for supporting the free end of said second panel.

11. In a railway sleeping car having a side wall and an aisle, a section space in the car de-

fined by end walls extending transversely from the side wall to the aisle, said section space having a lower seating area and a sleeping area spaced above the seating area, an auxiliary sleeping berth in said sleeping area comprising a fixed portion adjacent one of said end walls and a pair of folding panels including a first panel hingedly connected to said fixed portion and a second panel hingedly connected to the first panel whereby to provide a full length berth foldable intermediate its ends and adapted to be extended from folded closed position to open position extending substantially the full length between said end walls, means for supporting the intermediate hingedly connected portion of said panels, and means for supporting the free end of said second panel, the plane of said fixed portion and of the panels when extended to open position being sufficiently high in the section space to permit the seating of an occupant in the seating area when the berth is extended to open position.

12. In a railway sleeping car having a section space, end walls defining the length of said space, said section space having a lower seating area and a sleeping area spaced above the seating area, a folding berth for the sleeping area including a horizontal fixed portion at one end of the section space, a panel member hingedly connected with said horizontal portion and at least one other panel member hingedly connected with said member to provide a berth extendible from a vertical folded position adjacent said end of the section space to an open position on a horizontal plane coincident with said fixed portion at said upper level, and means for supporting said panels in extended position, said horizontal plane being sufficiently high in the section space to permit the seating of an occupant in the seating area when the panel members are extended to open position.

13. In a railway sleeping car having a section space, a seat in said space, a compartment in the space above the level of said seat, a berth for the section space associated with said compartment including a panel member hingedly connected with the compartment adjacent the bottom thereof, and a second panel member hingedly connected to said member, said panels by means of said hinged connections being extendible from a substantially vertical folded position closing said compartment to a horizontal position on a level with the bottom of the compartment to provide a bed extending substantially full length of said section space, said bed when in horizontal position being spaced above the level of said seat a distance whereby the seat is available for use while the bed is available for use.

14. In a railway sleeping car having a section space including a lower area for use during the day and an upper area for use at night, a compartment in the section space located in said upper area, a berth for the section space associated with said compartment including a panel member hingedly connected with the compartment, and a second panel member hingedly connected to said member, said panel members by means of said hinged connections being extendible from a folded position closing said compartment to an open position on a horizontal plane defining the level of said upper area to provide a bed extending substantially full length of said section space entirely independent of said lower area, and said horizontal plane being sufficiently high in the section space to permit the seating of an occupant in the lower area when the panel members are extended to open position.
